UNITED STATES PATENT OFFICE.

JACOB E. DAVIS, OF IRONTON, OHIO.

DESIGN FOR A LAMP-POST.

No. 37,742.

Specification for Design.

Patented Dec. 19, 1905.

Application filed November 10, 1905. Serial No. 286,764. Term of patent 14 years.

To all whom it may concern:

Be it known that I, JACOB E. DAVIS, a citizen of the United States, residing at Ironton, in the county of Lawrence and State of Ohio, have invented a new, original, and ornamental Design for a Lamp-Post, of which the following is a specification, reference being had to the accompanying drawing, forming a part thereof.

The figure is a front elevation of a lamp-post, showing my design.

I claim—

The ornamental design for a lamp-post as shown.

JACOB E. DAVIS.

In presence of—

A. P. KERR,
R. MATHER.
